(57) **CLAIM**

The ornamental design for this three piece storage table set, as shown and described.

DESCRIPTION

FIG. 1 is a perspective view of the main table of the three piece table set;

FIG. 2 is a front view of the main table of the three piece table set;

FIG. 3 is a side view of the main table of the three piece table set;

FIG. 4 is a top view of the main table of the three piece table set;

FIG. 5 is a bottom view of the main table of the three piece table set;

FIG. 6 is a perspective view of the main table of the three piece table set in an open position, with two identical end tables stored inside the main table;

FIG. 7 is a front view of the main table of the three piece table set in an open position, with two identical end tables stored inside the main table;

FIG. 8 is a back view of the main table of the three piece table set in an open position;

FIGS. 9 and FIG. 10 are side views of the main table of the three piece table set in an open position, with a side view of an end table, which is stored inside the main table;

FIG. 11 is a top view of the main table of the three piece table set in an open position, with two identical end tables stored inside the main table;

FIG. 12 is a bottom view of the main table of the three piece table set in an open position;

FIG. 13 is a perspective view of the main table in a closed position and two identical end tables of the three piece table set outside of the main table;

FIG. 14 is a perspective view of one of the two identical end tables with its top lid removed; and,

FIG. 15 is a perspective view of a top lid which has been removed from one of the two identical end tables.
